UNITED STATES PATENT OFFICE.

EDWARD E. FOSTER, OF BEVERLY, MASSACHUSETTS, ASSIGNOR TO C. C. BLAKE, INCORPORATED, OF BOSTON, MASSACHUSETTS, A CORPORATION OF NEW YORK.

THREAD MEASURER.

Application filed November 22, 1918. Serial No. 263,767.

To all whom it may concern:

Be it known that I, EDWARD E. FOSTER, a citizen of the United States, residing at Beverly, in the county of Essex and State 5 of Massachusetts, have invented certain Improvements in a Thread Measurer, of which the following description, in connection with the accompanying drawings, is a specification, like reference characters on the 10 drawings indicating like parts in the several figures.

This invention relates to sewing machines and is particularly concerned with sewing machines for heavy work such as harness 15 sewing, outsole stitching, and the like. Machines of this class usually are equipped with some form of mechanism for measuring off or drawing from the thread supply the length of threads required for each 20 stitch so as to limit definitely the amount of thread subjected to the manipulation of the sewing instrumentalities in each cycle of operations of the machine and thus enable the machine to pull up the 25 stitches uniformly. It is obvious that the length of thread required for each stitch will vary with the thickness of the work and the length of the stitch. Since the thickness of the work may vary in different 30 parts along which the sewing operation is to be performed, it obviously is desirable to have the thread measuring mechanism vary the length of thread automatically in response to variations in the thickness of the 35 work. The length of stitch usually does not vary in a given piece of work but the machine is adjusted for the desired length of stitch before the sewing operation is started and usually this adjustment is maintained 40 for a given lot of work. It is desirable, however, to adjust the length of thread supplied by the thread measuring mechanism to correspond to changes in the length of stitch since otherwise the machine will form 45 looser stitches when set for certain lengths than for certain other lengths, or else the locking or intersection of the threads, if the machine is of the lock stitch type, will come at different depths in the work.

50 It is the chief object of the present in-

vention to devise a thread measuring mechanism for sewing machines which will satisfy the requirements above outlined, which will be accurate and reliable in operation, which will require minimum of attention on the part of the operative or attendant, and which will require neither skill nor judgment on the part of the operative in making adjustments for different conditions.

To the accomplishment of these and other objects of the invention which will hereinafter appear, the invention provides certain novel combinations and arrangements of parts and details of construction, the nature 65 of which will be readily understood from the following description of one embodiment of the invention.

Referring now to the accompanying drawings,

Figure 1 is a side elevation of the more important parts of an outsole stitching machine equipped with a thread measuring mechanism embodying the present invention;

Fig. 2 is a rear elevation of certain parts of the machine shown in Fig. 1;

Fig. 3 is a side elevation showing the opposite sides of certain parts of the thread measuring mechanism shown in Fig. 1;

Fig. 4 is a vertical cross sectional view on the line 4—4, Fig. 3;

Fig. 5 is a plan view, partly in horizontal cross section, showing a detail of the construction of the mechanism shown in Fig. 3;

Fig. 6 is a vertical cross sectional view taken substantially on the line 6—6, Fig. 7, showing the mechanism for adjusting the length of stitch in the machine shown in Fig. 1; and

Fig. 7 is a vertical cross sectional view on the line 7—7, Fig. 6.

The sewing or stitching machine shown in the drawings forms the subject matter of co-pending application, Serial No. 153,161, filed March 7, 1917 in the name of Charles C. Blake, reference to which is made by permission. A detailed description of this machine is unnecessary for the purpose of disclosing the present invention but it may 100

2. facilitate an understanding of the construction shown to state that the sewing instrumentalities include a needle 2, mounted to reciprocate toward and from a work support or throat plate 4, an awl 3 and a looper 5 which presents a loop of needle thread to the needle in position to be caught by the hook of the needle and drawn up through the work. A loop thrower 7 passes this loop 10 of thread over a stationary shuttle located above the work and a cam-operated take-up lever 8 then acts on the needle thread to set the stitch. The work is clamped during the stitch-forming operation by means of a 15 presser foot 10 mounted on the lower end of a rod 11 which slides through the frame and is acted upon by a spring 12 to hold the presser foot 10 firmly in contact with the work. A cam-operated locking mechanism 20 is provided to lock the presser foot in its depressed or work-clamping position while the stitch is being made. The position of the presser foot 10 thus is controlled by the thickness of the work and it is locked in 25 said position while the stitch-forming instrumentalities act on the work. The various sewing instrumentalities are operated by cams fast on a main cam shaft 14 which is driven by spiral gears enclosed in the 30 housing 15, one of these gears being fast on the shaft 14 and the other fast on the vertical driving shaft 16.

The shoe S (Fig. 1) is mounted on a work support, indicated in general by the numeral 35 18, which operates between successive stitch-forming operations to feed the shoe step by step past the stitch-forming instrumentalities. The work supporting and feeding mechanism shown is of the character disclosed in pending application, Serial No. 40 113,722, filed August 8, 1916 in the name of Charles C. Blake. But, in the machine shown in the present application the horizontal shaft 19, which operates said mechanism, is driven by an adjustable mechanism 45 by means of which the length of each feeding movement, and consequently the length of each stitch formed, can be adjusted.

This driving mechanism is enclosed in 50 housings 20 and 21 and is best shown in Figs. 6 and 7. Referring to these figures, it will be seen that the upright shaft 16 has fast thereon a cam 22 having a cam path formed therein with driving portions and holding 55 portions. A pin wheel 24 mounted fast on a shaft 25 is provided with a series of radial pins or rolls which enter successively the path in the cam 22, so that the constant rotary motion of the shaft 16 is, by this 60 mechanism, transformed into an intermittent rotative movement of the shaft 25. This mechanical movement is fully disclosed in Patent No. 1,241,911, granted October 2, 1917. Four pinions indicated respectively 65 at 26, 27, 28 and 29 (Fig. 6) are mounted

fast on the shaft 25 and run constantly in mesh with gears indicated respectively at 30, 31, 32 and 33, all loosely mounted on the hollow shaft 34. This shaft is connected to the shaft 19.

The respective pairs of pinions and gears are made of different gear ratios and each gear is equipped with a clutch so that, while all the gears normally rotate freely on the hollow shaft 34, any one of the gears may be made effective to drive this shaft. These clutches are all alike and consequently a description of one only is necessary. As best shown in Fig. 7, each clutch includes a hub member 36 keyed to the shaft 34 and mounted within a recess formed in its respective gear. Two friction shoes indicated, respectively, at 37 and 38 (Fig. 7) are pivotally mounted in the hub 36 close to its periphery and they are provided with hook-shaped spring arms which enter slots formed in opposite sides of the shaft 34 and terminate in small knobs 40 that lie just within the bore of the shaft. By referring to Fig. 7 it will be seen that normally the gear 31 can rotate freely on the clutch hub 36 without effecting a rotative movement of the clutch, but if the ends 40 of the spring arms are forced outwardly they will apply sufficient pressure to the friction shoes 37 and 38 to cause them to grip the peripheral wall of the recess in the gear 31 and establish a driving engagement between this gear and the clutch hub 36, thus transmitting the rotative movement of the gear to the hollow shaft 34.

In order to render any one of the four gears shown effective to drive the shaft 34, a clutch actuator is provided which consists of a plunger 41 carrying a head 42 which slides in the bore of the shaft 34. A grooved roll 44 is secured fast to the outer end of the plunger 41 and the groove is engaged by pins mounted in the upper arm of a bell crank lever 46, Figs. 2 and 6, mounted fast on a shaft 48 which rocks in bearings formed in a bracket 50. The other arm 51 of said lever is movable over a segment plate 52 and carries a spring-pressed pin secured to a knob 54, the pin being adapted to enter any one of a series of holes 55 formed in said plate. These holes are so spaced apart that when the pin 54 is in any one of them the head 42 of the plunger 41 will be in engagement with one of the four pairs of the members 40; and the arrangement is such that when the lever 46 is in the position in which it appears in Fig. 1 the pinion 26 and gear 30 (Fig. 6) are effective to drive the shaft 34 and consequently to operate the work feeding mechanism. This pair of gears gives the shoe its slowest feeding movement or, in other words produces the shortest length of stitch. As the lever 46 is moved to withdraw the plunger 41 from the shaft 34, the

head 42 is moved successively into engagement with the different pairs of members 40 thus increasing the speed of the feeding movement of the work and thereby increasing the length of the stitches formed.

As above stated, the position of the presser foot depends upon the thickness of the work and the thread measuring mechanism with which the machine is equipped is so connected to the presser foot that a change in the thickness of the work operates automatically through a presser foot to change the length of thread delivered by the measuring mechanism to the stitch forming instrumentalities.

The thread T is led from the wax pot, or other supply, through a thread locking mechanism indicated at 56, (Fig. 3) over a pin 58 on the end of a thread pulling lever 60, through another thread lock 62 to a roll 64, Fig. 1, and thence over the roll on the end of the take-up lever 8 to the looper 6. The thread locks 56 and 62 are alternately actuated so that the thread is always under the control of one of these locking devices. The lock 56 comprises a stationary bracket 65 and a member 66 pivotally mounted in one arm of a rocker 67 so that it can tip in the same plane in which the rocker tips. This rocker is pinned to a short shaft 68 supported in a stationary bearing and an arm 69 is pinned to the opposite end of this shaft and carries a roll 70, Fig. 3, which runs on the peripheral cam face 72 of the cam 73 mounted fast on the shaft 14. A spring 74 acts on this arm 69 in a direction to hold the roll 70 in contact with the cam face 72 and thus tends to hold the thread clamping member 66 against its co-operating member 65, or, in other words, this spring 74 tends to close the thread clamp 56.

The other thread clamp 62 comprises a thread-engaging device 76 constructed and mounted on the rocker 67 in substantially the same manner as is the member 66. The thread-engaging face of the members 76 and 66 are grooved as shown in Figs. 4 and 5. This member 76 co-operates with an upper spring pressed thread-engaging member 78, having a tongued portion to enter the groove of the part 76, and having its shank positioned in a hole 79 drilled in the machine frame. A coiled spring 80 encircles a reduced part of this shank and tends constantly to hold the member 78 in engagement with its co-operating thread clamping member 76. The range of movement of the arm 69 and consequently of the rocker 67, is such that the thread clamp 56 is open at certain times and closed at other times, but the thread lock 62 always remains closed, the rocking of the part 67 merely being sufficient to increase or decrease the grip of the members 76 and 78 on the thread.

The thread drawing movement of the lever 60 takes place while the clamp 56 is open. This movement is produced by cam connections including a link 83 which connects the rear end of the thread pulling lever 60 with one arm of a bell crank lever 84, (Fig. 1), the other arm of which carries a roll 85 running in a path 86 of a cam fast on the shaft 14. This mechanism thus gives the lever 60 a stroke of fixed length.

The variation in the thread drawing action of this lever required to enable it to pull more or less thread depending upon a change in the thread requirements, due to a variation in the thickness of the work, is produced by so mounting the lever 60 with reference to the thread clamps 56 and 62 that more or less of its stroke may be made effective to draw thread from the supply. For this purpose the fulcrum 82 of the thread pulling lever 60 is mounted on one arm of a bell crank lever 88 which moves on a fixed fulcrum 89, Fig. 3, and the other arm of the lever 88 carries the fulcrum pin 90 of a floating lever 92. A link 94, pivoted to the lower end of a floating lever 92 at 93, is threaded at its lower end to receive an adjusting nut or wheel 95 which is mounted between stationary brackets 95', Fig. 2, that prevent it from moving longitudinally of the rod 94 but permit it to rotate so that this rotary motion moves the rod 94 longitudinally in one direction or the other depending on the direction of the rotative movement of the nut 95. The parts 95' are supported by an arm projecting from the stationary bracket 50. A link 96 pivoted to the upper end of the floating lever 92 at 97, connects this lever with one arm of a bell crank lever 98, the other arm of which is pivotally connected to the presser foot plunger 11.

It will now be understood that when the thread measuring operation takes place, the rocker 67 will be tipped about the axis of the shaft 68 in a clock-wise direction so as to open the thread lock 56 and to increase the grip of the thread lock 62 on the thread. The cam connections of the lever 60 then rock this lever about its fulcrum 82 in a clockwise direction (referring to Fig. 3) thus moving the pin 58 upward with reference to the thread locks and causing it to draw thread from the supply through the open thread lock 56. If desired two pins 99 may be positioned on the hub of the rocker 67, as shown in Figs. 3 and 5, to guide the thread as it leaves the thread lock 56 and enters the lock 62. These pins also render the thread measuring action more accurate. When the thread drawing stroke of the lever 60 has been completed, the cam path 72 permits the spring 74 to move the rocker 67 in a counter clock-wise direction thus closing the thread lock 56 and reducing the grip of the lock 62 on the thread.

The sewing instrumentalities then draw the loop of thread just measured off through the lock 62, which acts during this operation merely as a thread tension device. The 5 thread lock 56 prevents the pulling of thread directly from the supply after the thread measuring operation has been completed, while the thread lock 62 operates during the thread measuring operation to prevent the 10 pin 58 from drawing thread back away from the sewing instrumentalities.

It will be evident from an inspection of Fig. 3, that changes in the position of the floating lever 92, produced by changes in the 15 thread requirements, act through the bell crank lever 88 to raise or lower the fulcrum 82 of the thread pulling lever 60. Consequently, while the actuating mechanism for this lever gives it a stroke of fixed length, 20 the part of this stroke that is effective to draw thread from the supply will be determined by the position of the fulcrum 82 since, if this fulcrum point is raised or lowered, the limits of the reciprocating movement of the pin 58 will be moved up or down longitudinally of the path of travel of the 25 pin. Obviously, if the upper limit of this movement is raised with reference to the thread-locks, the pin will draw more thread from the supply at each thread measuring operation, and if lowered, it will draw less thread. Since the adjustment of this fulcrum is controlled by changes in the adjustment of the nut 95 or in the thickness of the 30 work the length of thread measured out in each cycle will always vary automatically with changes in the thickness of the work and it can also be adjusted manually.

Assuming, for instance, that the parts are 40 in the relative positions in which they appear in Fig. 1 and that a thicker part of the work is moved under the presser foot 10, the consequent raising of the presser foot will act through the bell crank lever 98 and link 45 96 to swing the floating lever 92 about the pivot 93 as a fulcrum, and this change in the position of the lever 92 will act through the pivot 90 and the bell crank lever 88 to raise the fulcrum 82 of the lever 60 and therefore 50 cause this lever to measure off a longer length of thread.

When a thinner piece of work is moved under the presser foot 10 the connections just described operate to lower the fulcrum 55 82 and thus cause the lever 60 to measure off a shorter length of thread. The mechanism is designed to make the variation in the length of thread proportional to the change in the thickness of the work so that the 60 stitches will be set up with a uniform tension and the lock or intersections of the thread in the work will come at a uniform distance from one face of the work.

The other adjustment is provided to enable the operator to adjust the mechanism so

that it will measure off accurately the length of thread required for each stitch when the length of stitch is changed. In order to facilitate this operation the thread measuring and stitch length adjusting mechanisms preferably are provided with correlated designations for their adjustments so that nothing is left to the judgment or discretion of the workman. This may conveniently be done by numbering the adjustments for the stitch 75 length setting mechanism, as indicated on the sector 52 in Fig. 1, and then correspondingly numbering the positions to which the nut 95 should be turned to effect the required adjustment of the thread measuring mechanism for the new adjustment of the stitch length adjusting mechanism. As shown in Figs. 1 and 2 the lever 51 is set for the shortest length of stitch. If this lever should now be adjusted to the next hole above, designated at 2, to cause the machine to make stitches of the next longest length, then the operator should turn the nut or wheel 95 until the mark opposite the number 2 is brought opposite a fixed mark, such as that indicated at 100, on a stationary part of the machine. The numbered marks on the wheel 95 are determined by trial or calculation to designate the required adjustments of the thread measuring mechanism for the respective changes in length of stitch. It is obvious that any suitable number of such adjustments can be made and that a different set of designations could be used, the point being that the adjustments for length of stitch bear designations corresponding to those required to be made in the thread measuring mechanism.

The thread delivering movement of the lever 60 and pin 58 is so timed with reference to the movements of the take-up mechanism and the stitch forming instrumentalities that a substantially uniform tension is maintained on the thread between the thread measuring mechanism and the stitch forming members while a stitch is being formed.

In other words, the part 58 is moved at such a speed that it delivers thread to the stitch forming instrumentalities at substantially the rate at which they require it and the presence of slack thread between these instrumentalities and the thread measuring mechanism thus is avoided.

It will now be understood that the thread measuring mechanism provided by this invention is very simple in construction, reliable in operation, and is not subject to rapid wear or deterioration. It is entirely automatic in its action in responding to changes in the thickness of the work and the 120 adjustment for changes in the length of stitch is exceedingly simple. The mechanism has proved exceeding accurate in practice.

It is obvious that the particular embodi-

ment of the invention may be departed from in many particulars without departing from the spirit or scope of the invention. For instance, instead of making the rod 94 of the thread measuring mechanism adjustable in the manner above described, this adjustment may be effected by means of a turn-buckle, as indicated at 102, Fig. 1. The illustrated embodiment of the invention is susceptible of substantial modification while still retaining the essential characteristics of the invention.

What is claimed as new, is:

1. In a sewing machine, the combination 15 of stitch forming instrumentalities and means for puncturing the work to receive the needle, thread measuring mechanism operative to supply a measured length of thread to said instrumentalities in each 20 cycle of operations of the machine, means independent of said stitch forming instrumentalities and work puncturing means for feeding the work, and mechanism for adjusting the length of stitch, said thread 25 measuring and stitch length adjusting mechanism being correspondingly adjustable to enable the workman to make the adjustment of one mechanism correspond to that of the other.
2. In a sewing machine, the combination 30 of stitch forming instrumentalities, thread measuring mechanism operative to supply a measured length of thread to said instrumentalities in each cycle of operations of 35 the machine, and mechanism for adjusting the length of stitch, said thread measuring and stitch length adjusting mechanisms being independently adjustable but having correlated designations for their adjustments to enable the workman to make the 40 adjustment of one of said mechanisms correspond to that of the other.
3. In a sewing machine, the combination 45 of stitch forming instrumentalities, a thread measuring mechanism for supplying the

stitch forming instrumentalities with the length of thread required for each stitch, and operative to vary the length of thread so supplied automatically in response to changes in the thickness of the work, means 50 for adjusting the length of stitch, and means for adjusting the thread measuring mechanism to vary the length of thread delivered thereby in each cycle of operations of the machine in accordance with 55 changes in the length of stitch.

4. In a sewing machine, the combination of stitch forming instrumentalities, thread measuring mechanism for supplying a measured length of thread to said instrumentalities in each cycle of operations of the machine, said mechanism being constructed and arranged to vary said length of thread automatically in response to variations in the thickness of the work, a 60 threaded adjustment for varying the length of thread supplied by said mechanism in each cycle of operations of the machine independently of the thickness of the work, and mechanism for adjusting the length of 65 the stitch made by the machine.

5. In a sewing machine, the combination of stitch forming instrumentalities, thread measuring mechanism for supplying a measured length of thread to said instrumentalities in each cycle of operations of the machine, said mechanism being constructed and arranged to vary said length of thread automatically in response to variations in the thickness of the work, automatic mechanism for feeding and swinging the work step by step past said instrumentalities, mechanism for adjusting the lengths of said steps to adjust the length of stitch, and a manual adjustment for said thread 75 80 85 measuring mechanism.

In testimony whereof I have signed my name to this specification.

EDWARD E. FOSTER.
